UNITED STATES PATENT OFFICE.

THOMAS W. PAXTON, OF PORTLAND, OREGON, ASSIGNOR TO SHIPBUILDERS PNEUMATIC TOOL CO., OF PORTLAND, OREGON.

FLUID-OPERATED TURBINE-ENGINE.

1,283,423.

Specification of Letters Patent. Patented Oct. 29, 1918.

Application filed October 8, 1917. Serial No. 195,477.

To all whom it may concern:

Be it known that I, THOMAS W. PAXTON, a citizen of the United States, and a resident of the city of Portland, county of Multnomah, State of Oregon, have invented a certain new and useful Improvement in Fluid-Operated Turbine-Engines, of which the following is a specification.

The particular object of my invention is to provide an air driven turbine especially adapted for being used as the driving element of a hand-guided tool, such, for example, as a planing tool; and to this end so designing and building my turbine that the same will be light so as to be easily handled, but have sufficient power to efficiently do its work.

Some of the features by which I attain this result consist in so arranging the circumferential pockets of the turbine that they will widen in vertical plane toward the mouth, and when exposed to the impact of the jet of the driving fluid the roof thereof is inclined at such angle as to present an effective surface to said jet. I also provide a plurality of inlet ports, distributed equidistant about the circumference of the rotor; and with these features I combine others which will hereinafter be fully described.

My invention is fully illustrated in the accompanying drawings, in which:

Figure 1 is a side elevation, partly in section;

Fig. 2 is a rear-end view, half in vertical transverse section, taken through the center of axis of rotation of the rotor;

Fig. 3 is a larger-scale sectional, fragmental view of the periphery of the rotor and portions of the inclosing bushing and casing, illustrating the construction of the pockets of the rotor relative to the inlet ports; and

Fig. 4 is a partial plan section taken on a line 4-4 of Fig. 2.

a is a cutter-head, cored out to make the same light, and provided with integral shouldered stub axles *b*. On the latter are mounted hollow casings *c*, having removable covers *d*. A rotor *e* is rigidly mounted on each stub axle *b*. A convenient way of accomplishing this being to thread the rotor on said stub axles and so arrange the thread as to tighten up while the rotor is rotating in

the driving direction. Ball bearings *f* are interposed between the bearing faces, as shown. The annular bushings *g* provide fluid-tight covers for the open sides of the fluid chambers *j* extending circumferentially about the rotor, and confine the motor fluid to the inlet ports *h*.

The pockets *e'* of the rotors are formed as follows: Taking a tangential line *x* (Fig. 3), an angular line *x'* is drawn at 24° therefrom, which line describes the floor *e'* of the pockets; and a line drawn under and parallel to the line *x'* describes the roof of the adjacent pocket. The pockets are therefore given a V-shaped form, or, in other words, enlarged toward the mouth in longitudinal section.

The inlet ports *h* in the bushing *g* are formed as follows: Taking a tangential line *y* (Fig. 3), an angular line *y'* is drawn at 20° therefrom, and describes the parallel faces of the roof and floor of the inlet port.

By this construction, when a pocket is brought into registration with an inlet port, the former will be so relatively arranged as to expose the surface of its roof at an inclination to the jet of driving fluid, and in this way render the impact of the latter more efficient. There are a plurality of fluid inlet ports *h* (the drawing showing eight) distributed equi-distant about the periphery of the motor. As many pockets are formed in the periphery of the motor as can be conveniently accommodated.

The fluid chamber of the two sides of the casing are connected by a passageway *k*, which is connected at *k'* with a source of motor fluid. As shown in Fig. 1, the passageway *k* may be conveniently made of a casting screwed in place as shown in Figs. 1 and 4.

l designates the blades of the cutter-head secured in place by screw bolts *m*. For the safety of the operator the cutter-head is inclosed by a cover made of sections *n*, *n'*, hinged together at *n* and screwed to the radial lugs *o'* of the cutter-head, as shown in Fig. 1.

The cutter-head is supported on independently adjustable shoes *o*, *p*, located, respectively, rearward and forward of the axis of rotation of the cutter-head. The rear cut-

ter-head comprises side plates between which is secured a block of wood o^2 , serving as the bearing member. The sides are cut away, as at o^3 , so as to expose the knives passing such point. The front ends of the sides of the rear shoe extend to the front of the case sides of the turbine, and are hinged on a transverse shaft q . Slots o^4 are provided in the rear portions of the sides, as shown in Fig. 1, 10 and through such slots extend a transverse shaft or clamping screw bolt r , a nut r' being threaded on one extremity of the latter. The slot o^4 is made of sufficient width to accommodate the arcuate movement of the rear 15 shoe on the clamping screw r . A double-ended screw s , provided with opposite threads and milled finger-piece or head, threads at one end into the casting k , and the other end threads into a bar o^5 set into 20 the upper face of the block of wood o^2 . The sides of the rear shoe extend rearward, as shown in Fig. 3, and the block of wood 2 is extended to such length as to counter-balance the weight of the cutter-head. The extended part of the block o^2 is provided with 25 a hand-grip t , as on the ordinary plane. By the screw r the cutter-head may be adjusted relatively to the initial rough work which the knives are to do. When this 30 work has been accomplished the rear shoe is readjusted, as shown in Fig. 1. The front shoe p is depended upon to determine the depth of the cut of the knives in the finishing work, also to allow for the 35 wear of the knives. The front shoe comprises the sides p' , connected at the lower end by a transverse web p^2 , serving as a bearing face. The sides p' are provided with slots p^3 , in which bear pins v , and portions are cut away, as at p^4 , in which bears 40 the cam q' on the transverse shaft q . One end of the latter is provided with a milled head by which to rotate it and thereby adjust the front shoe as desired. The other 45 end of the cam shaft q is provided with a milled nut q^2 by which the cam shaft may be clamped in place as adjusted. Since the forward ends of the sides of the rear shaft pivot on the cam shaft q , the axis of which is parallel to the axis of rotation of the cutter-head, the bearing face of the rear shoe is always maintained square with the roof, and a cut of uniform depth by the knife is assured. 50 The features shown and described regarding the shoe, by which the planer shoe is supported on the work are also my invention, and form the subject matter of Letters Patent filed simultaneously with this application. 60

I claim:

1. In a turbine engine of the character described, the combination of a rotor provided with peripheral pockets widening in a vertical plane toward the mouth, and the plane

of the roof of the pockets being inclined at an oblique angle to the line of the jet of driving fluid.

2. In a turbine engine of the character described, the combination of a rotor provided with peripheral pockets, the planes of the floors of these pockets being described by a line drawn upward approximately at an angle of 24° from a line tangential to the rotor, and the planes of the roofs of the pockets being described by a line extending parallel with the floor of the preceding pocket, and the ports of the driving fluid having an axis coincident with a line drawn upward at an angle of approximately 20° from a line tangential to the rotor. 70

3. In a turbine engine of the character described, the combination of a rotor provided with peripheral pockets widening in a vertical plane toward the mouth, the planes of the floors of these pockets being described by a line drawn upwardly approximately at an angle of 24° from a line tangential to the rotor, and the planes of the roofs of the pockets being described by a line extending 85 parallel with the floor of the preceding pocket, and the ports of the driving fluid having an axis coincident with a line drawn upward at an angle of approximately 20° from a line tangential to the rotor. 90

4. In a turbine engine of the character described, the combination of a rotor provided with peripheral pockets, and the plane of the roof of the pockets being inclined at an oblique angle of approximately 4° to the 100 line of the jet of driving fluid. 95

5. In a turbine engine of the character described, the combination of a rotor provided with peripheral pockets widening in a vertical plane toward the mouth, and the plane 105 of the roof of the pockets being inclined at an oblique angle of approximately 4° to the line of the jet of driving fluid.

6. In a turbine engine of the character described, the combination of a rotor, a housing providing a concentric fluid pressure chamber circumferentially about the rotor and provided with ports, for the driving fluid, having an axis coincident with a line drawn upward at an angle of approximately 20° 110 from a line tangential to the rotor, the rotor having circumferential pockets the planes of the floors of which are described by a line drawn upward approximately at an angle of 24° from a line tangential to the rotor, 115 and the planes of the roofs of these pockets being described by a line extending parallel with the floor of the preceding pocket. 120

7. In a turbine engine of the character described, the combination of a rotor, a three-sided housing providing a concentric fluid pressure chamber circumferentially about the rotor, a bushing composing the floor of such housing and provided with a port, for the driving fluid, having an axis coincident 125

with a line drawn upward at an angle of approximately 20° from a line tangential to the rotor, the rotor having circumferential pockets the planes of the floors of which are described by a line drawn upward approximately at an angle of 24° from a line tangential to the rotor, and the planes of the roofs of these pockets being described by a

line extending parallel with the floor of the preceding pocket.

8. The combination specified in claim 7 provided with a plurality of fluid inlet ports distributed equi-distant about the circumference of the rotor.
